UNITED STATES PATENT OFFICE.

WILLIAM H. CARROLL, OF JERSEY CITY, NEW JERSEY.

ILLUMINATED STREET-CAR SIGN.

SPECIFICATION forming part of Letters Patent No. 531,905, dated January 1, 1895.

Application filed October 6, 1894. Serial No. 525,125. (No model.)

To all whom it may concern:

Be it known that I, WILLIAM H. CARROLL, of Jersey City, in the county of Hudson and State of New Jersey, have invented a new and Improved Illuminated Street-Car Sign, of which the following is a full, clear, and exact description.

The object of the invention is to provide a new and improved illuminated street carsign, arranged to readily distinguish a car for a desired route, and to prevent persons from boarding the wrong car during the night.

The invention consists of an illuminated sign indicating the route of the car and arranged on the roof of the latter, and a reflector for the said sign to permit of conveniently reading the sign for a considerable distance ahead of the car.

The invention also consists of certain parts and details and combinations of the same, as will be fully described hereinafter and then pointed out in the claims.

Reference is to be had to the accompanying drawings, forming a part of this specification, in which similar letters of reference indicate corresponding parts in all the figures.

Figure 1 is a front elevation of the improvement as applied. Fig. 2 is an enlarged sectional front view of the improvement, on the line 2—2 of Fig. 3; and Fig. 3 is a transverse section of the same, on the line 3—3 of Fig. 2.

In cities and other places where a number of cars leave a terminal station to travel on different routes, or a number of cars for different routes travel for a distance on the same track or tracks arranged one alongside the other before switching off to their special routes, it is difficult for persons to readily distinguish the car for a particular route during the night time, and hence it frequently happens that persons board the wrong car, and are consequently carried in the wrong direction. To avoid this is part of the invention, presently to be described in detail.

On the roof A of the car or other vehicle, and at the end thereof is secured a suitable base B supporting at one side a lamp casing C containing a lamp of any approved construction, and provided at its outer side with a door C' for giving access to the interior of the sign and to the lamp contained therein.

On the inside of the door C' is arranged

a reflector C² for throwing the rays of light emanating from the lamp to the opposite side C³ and into and through an opening C⁴ formed in this side C³. This opening C⁴ registers with an apertured trunnion D rigidly secured to the outside of the side C³, see Fig. 2, and this trunnion D forms the bearing of the head E' of a sign E having its other head E² formed with a solid trunnion E³, mounted to turn in suitable bearings arranged on a bracket F secured to the base B, and on the outer end of the said trunnion E³ is fastened a crank arm E⁴ adapted to be taken hold of by the operator in charge of the car, so as to turn the sign to bring the desired side into a forward or front position, as hereinafter more fully described.

The sign E is made in the shape of a casing having heads E' and E², connected with each other by sides E⁵ made of glass or other transparent or translucent material, and with such legends printed or otherwise formed thereon as indicate the route or routes of the car.

As illustrated in the drawings, the sign E is provided with four sides E⁵, of which one is brought to the front by the operator turning the crank arm E⁴ into the proper position. The other three sides are protected from the rays of light from the lamp contained in the casing E, by a reflector G held stationary within the sign E, the said reflector being approximately U-shaped in cross section as is indicated in Fig. 3, and its open end is toward the side E⁵ held in front at the time.

The reflector G is provided with an apertured head G' loosely mounted on a boss E⁶ projecting from the inside of the head E², and the said reflector is provided with a second apertured head G² fitted onto the hollow trunnion D, and formed with an inwardly extending lug G³ engaging a notch E' in the said fixed trunnion D (see Fig. 3) so that the said reflector G is held in a fixed position, at the same time permitting the sign E to be revolved by the operator manipulating the crank arm E⁴ to bring the desired side E⁵ to the front. Now, it will be seen that the rays of light projected sidewise into the sign casing are reflected by the reflector G in a forward direction, so that the frontside E⁵ of the sign E is illuminated, and consequently the legend thereon is visible from a point a considerable distance ahead of the approaching car.

Now, it will be seen that by the arrangement described, the operator in charge of the car is at all times enabled to turn the sign E in such a position that the side indicating the route 5 of the car is visible to persons desiring to board the car, and prevents parties from selecting the wrong car. It will further be seen that by the specially constructed reflector G, the remaining sides of the sign are not illuminated 10 by the rays of light from the lamp in the casing C, so that mistakes are avoided.

Having thus fully described my invention, I claim as new and desire to secure by Letters Patent—

15 1. In an illuminated sign for street-cars and the like, the combination of a casing adapted to contain a lamp and having an aperture in its wall, a trunnion arranged adjacent to the lamp casing and having an aperture corresponding 20 with the aperture in the wall thereof, and a tubular casing rotatively mounted on said trunnions with its end adjacent thereto open and adapted to receive light through the aperture therein, and transparent signs

mounted in the sides of said tubular casing, 25 substantially as set forth.

2. In an illuminated sign, the combination of a casing adapted to receive a lamp and having an aperture in its wall, a slotted trunnion arranged adjacent to the lamp casing 30 and having an aperture formed through it corresponding with the aperture in the wall thereof, a bracket aligned with the trunnion, a tubular sign having one end provided with a head journaled in said bracket and its other 35 end provided with a tubular head adapted to turn on the apertured trunnion, a trunnion located at the opposite end of the tubular casing, and a reflector having ring-shaped heads formed at its ends encircling said trunnions, one of said heads having a lug which projects inwardly and is adapted to engage the slot in the apertured trunnion.

WILLIAM H. CARROLL.
